STRIP FORMING MOLD

Anton H. Narrow, Memphis, Tenn.

Application December 5, 1949, Serial No. 131,164

5 Claims. (Cl. 22—136)

1

This invention relates to certain new and useful improvements in a mold or die for forming a continuous strip or bar of soft metal, particularly of type metal and similar alloys, which mold may be used in connection with an extrusion process or may be used in a process in which the cast metal may be drawn or pulled from the die as it emerges, or such extrusion or pulling action may be combined.

Specifically the present invention relates to new and useful improvements in the spacing members, conventionally heretofore employed in connection with similar dies or molds and in a new entrance arrangement into the channel forming the interior of the mold.

Heretofore molds of the same general character have been employed in the formation of strips of the character mentioned, particularly for use in the printing art in the formation of rules, lines and the like, and the strips thus formed have essentially constituted ribbon-like, flat, continuous members formed by the solidification of the molten type-metal or other alloy within the mold, the finished strip being withdrawn or extruded from the exit end of the mold.

In the preparation of such strips for use as rules in printing by which a thin straight line is imprinted upon a page as desired, it has been customary to form along one edge of the strip a bevel or shaped edge with the apex of the bevel forming the portion used to imprint the line upon the page. It has been found, due to the properties of the alloys commonly used in type-metal, that, unlike other metals, there is an expansion of such type-metal alloys upon cooling from molten state to a solid state with the result that it has heretofore been customary to provide a microscopic divergence between the upper and lower edges of the channel of the previous molds to compensate for such expansion and to permit ease of operation in the continuous production of the desired strips. It is frequently found that the strips, formed in molds of conventional type having such diverging upper and lower edges, are improperly burnished and the printing edge of the prepared strip has frequently been found to be pitted and otherwise defective in a manner undesirable in connection with the printing art.

The principal object of this invention is to provide a mold for forming strips of type-metal which includes means for burnishing the printing edge of the formed strip to eliminate therefrom any undesired pits and other irregularities.

A further object of the invention is to improve the arrangement of the entrance to such molds

2

through which molten metal is introduced into the mold so as to insure the introduction of the molten metal to the printing-edge-forming portion of said mold.

5 A further object of the invention is to provide a mold for forming strips which includes opposite side members forming sides of the mold channel and upper and lower longitudinal spacers spacing the side members apart and constituting the upper and lower edges of the mold channel, in which one of the spacers is scarfed for the formation of a fine line printing surface along one edge of the formed strip and the scarfed spacer adjacent the exit end of the channel converges toward the opposite spacer to reduce the width of the channel, the cast strip being drawn beyond the reduced width portion.

10 A further object of the invention is to provide such a mold in which the aforesaid scarfed spacer and converging end section is disposed as the upper spacer of the mold.

15 A further object of the invention is to provide such a mold in which the scarfed spacer is converged toward the opposite spacer along a gradual arc.

20 A further object of the invention is to provide a mold for forming strips in which the entrance to the mold channel is restricted by a block member, which block member lies intermediate the upper and lower spacers and is spaced from both said spacers.

25 And a further object of the invention is to improve the design, construction, utility and efficiency of molds for forming strips.

30 The means by which the foregoing and other objects of the present invention are accomplished and the manner of their accomplishment will readily be understood from the following specification upon reference to the accompanying drawings, in which:

35 Fig. 1 is a side elevational view of the mold of the present invention with a strip shown emerging therefrom.

40 Fig. 2 is a sectional elevational view taken on the line II—II of Fig. 1.

45 Fig. 3 is a sectional view taken on the line III—III of Fig. 2.

50 Fig. 4 is a fragmentary view similar to Fig. 3 on a greatly enlarged scale illustrating a preferred embodiment of the converging longitudinal spacer of the present invention; and

55 Fig. 5 is a view similar to Fig. 4 of a variation in the embodiment of the converging spacer.

Referring now to the drawings in which the various parts are indicated by numerals, the

3

mold of the present invention consists of a pair of side members 11 which are substantially identical, but which, as indicated in Fig. 2, may be of differing thicknesses, and to each of which is preferably affixed a side channel face or liner 13, liners 13 being preferably separate elements substantially identical with those shown in my co-pending application, Serial No. 115,541, although it will be understood that insofar as the present invention is concerned it may be used equally as well in connection with those molds in which the inner liners 13 are integral with side members 11 and are employed as the sides of the mold channel. Interposed between the channel liners 13 and between the side members 11 are longitudinal upper and lower spacers 15, 16 which are preferably of substantially rectangular shape, extend from end to end of the mold, maintain spacing between the channel liners 13 and respectively form the upper and lower edges of the mold channel. It will be seen that channel liners 13 and spacers 15, 16 form a channel extending from end to end of the mold and terminating in an exit opening 17.

Preferably lower spacer 16 is provided with a flat straight upper edge 18 so as to form a relatively straight edge along the lower edge of a strip formed in the mold. The lower edge 19 of upper spacer 15 is preferably scarfed as at 19A to form a beveled elongated recess along the lower edge 19 which is effective to impose a sharpened printing edge 20 on the strip 21 formed in the mold and to thereby provide for the printing of a fine line when strip 21 is so employed.

Preferably, as is conventional, lower edge 19 of upper spacer 15 diverges minutely away from upper edge 18 of lower spacer 16 through a majority of the length of the respective liners. Adjacent the exit end 17 of the channel formed in the mold, lower edge 19 of upper spacer 15 is provided with a curved portion 22 which converges toward upper edge 18 of lower spacer 16 so as to restrict exit opening 17, with the maximum restriction being preferably formed closely adjacent opening 17 as at 23.

It will be observed that in the drawings illustrating the present invention the curvature of curved end portion 22 of lower edge 19 of spacer 15 is preferably a microscopic curvature, being substantially exaggerated in the drawings for the purpose of illustration. It will, however, be understood that although the microscopic character of this curvature is preferred it is not intended that the present invention be limited to such microscopic dimension. It has been found that the spacing between the respective edges 19, 18 of upper and lower spacers 15, 16 is preferably narrowed from the point of beginning of curved portion 22 to the point 23 of maximum curvature in a range lying between .003 inch and .010 inch.

Adjacent the entrance end of the mold, the device is preferably provided with a block 25 which is of substantially the same thickness as the thickness of spacers 15, 16, and lies in contact with inner channel liners 13. Block 25 is positioned to begin substantially flush with the entrance end of the mold and to extend therein a minor distance. The upper edge of the block 25 is preferably spaced below scarfed lower edge 19 of spacer 15 to form an upper inlet passageway 27 intimately associated with the scarfed edge of spacer 15, so that the upper

4

edge of passageway 27 is longitudinally aligned with the scarfed edge, and the lower edge of the block is also spaced above upper edge 18 of spacer 16 to form a conventional lower inlet passageway 29. Block 25 is preferably maintained in position by suitable dowel pins 31 which extend through the block and maintain it in alignment. Preferably additional dowels 33 are provided to maintain the alignment of spacers 15, 16, and the entire device is preferably detachably secured by suitable screws 35.

In the use of the device it is assembled as described and molten type-metal is introduced as through a suitable spout 37 into the entrance end of the device. Preferably the molten metal is supplied to spout 37 by a suitable pressure device, not shown, so that it is introduced through passages 27, 29 into the interior of the mold under a suitable pressure.

The molten metal flowing through upper passageway 27 is enabled to flow directly into the scarving 19A of lower edge 19 of upper spacer 15 and is enabled to quickly and properly fill the beveled scarving so as to begin the proper formation of printing edge 20 without depending upon the inward flow of molten metal introduced through passage 29. In this manner introduction of the molten metal into the scarfed edge-forming portion is insured. As the introduction of molten metal through spout 37 is continued the metal is advanced along the interior of the channel between liners 13 and upper and lower spacers 15, 16. The metal continues in a molten state for a substantial distance in its passage through the mold and begins to solidify, preferably beyond the mid point of movement toward discharge end 17 and emerges from the discharge end in solid strip form. Preferably an intermittent pulling force is applied to the emerged end of strip 21, a symbolic pulling device being indicated at 39.

As strip 21 passes from the mold, printing edge 20 frictionally contacts the converging curved portion 22 of upper spacer 15 and as the strip is drawn therebeyond the printing edge is effectively burnished by the frictional engagement with the curved portion.

It will readily be seen that in view of the relatively soft characteristics of the alloys employed conventionally in type-metal the above described frictional contact is highly effective to apply a burnish and polish to the printing edge 20 and to eliminate therefrom irregularities, pits or other defects which have frequently characterized printing strips produced by conventional molds. In some instances it is considered desirable to converge the terminal end of spacer 15 more abruptly than along the gradual arc of curved portion 22. Under such conditions a more sharply arced portion 22A may be provided adjacent the discharge opening 17. Portion 22A obviously functions in manner substantially identical to that already described in connection with portion 22.

It will be understood that the foregoing specification has described the physical aspects of the preferred embodiment of the present invention, but that other forms and embodiments thereof may be readily accomplished without departing from the scope of the invention, and it will, therefore, be understood that the present invention is not intended to be limited to the precise embodiment shown, except as defined in the appended claims.

I claim:

1. In a mold for forming metallic strips which

comprises a pair of sides, a pair of flat, inwardly facing, side liners, respectively supported by said sides, an upper spacer and a lower spacer, said spacers extending longitudinally of and being interposed between said liners to space said liners apart horizontally and being vertically spaced apart, said liners and the proximate edges of said spacers defining a flat, strip-forming channel, having an entrance end and a discharge end, the said proximate edges diverging from said entrance end throughout a majority of the length of said spacers, one of said spacer edges remote from said entrance end having a minor portion converging toward the other said spacer, the other said spacer edge being straight throughout its length from end to end of said channel.

2. A device in accordance with claim 1 in which said converging portion is curved along a gradual arc.

3. A device in accordance with claim 1 in which said upper spacer includes said converging portion.

4. In a mold for forming metallic strips which comprises a pair of sides, a first spacer, a second spacer spaced from the first spacer, said spacers extending longitudinally of and being interposed between said sides to space said sides apart, said sides and the proximate edges of said spacers defining a flat, strip-forming channel having an entrance end and a discharge end, one only of said spacer edges remote from said entrance end

and adjacent said discharge end having a minor portion converging toward the other said spacer, the said other spacer being straight throughout its length from end to end of said channel, whereby to restrict said discharge end with the restriction being located on one edge only of the discharge end to burnishingly contact one edge of a strip passing through said discharge end.

5. A device in accordance with claim 4 in which said minor converging portion is an arcuately curved portion.
